UNITED STATES PATENT OFFICE.

FREDERICK N. DU BOIS, OF NEW YORK, N. Y.

METHOD OF AND MEANS FOR PROTECTING THE BORES OF HEAVY GUNS FROM EROSION.

1,044,360.

Specification of Letters Patent. Patented Nov. 12, 1912.

Application filed April 25, 1910. Serial No. 557,560.

To all whom it may concern:

Be it known that I, FREDERICK N. DU BOIS, a citizen of the United States, and a resident of the borough of Manhattan, in the county, city, and State of New York, have invented certain new and useful Improvements in the Method of and Means for Protecting the Bores of Heavy Guns from Erosion, of which the following is a specification.

In the use of heavy guns of the modern high power class it has been found, that, at each discharge, the walls of the bore, when a projectile is employed, are so eroded either by the enormous pressure to which they are subjected by the gas evolved in the burning of the explosive, or by the heat liberated thereby, or by both together, that after a certain number of discharges, usually less than one hundred, the walls of the bore are so eaten away as to render the gun inoperative and incapable of further use, until the same is re-bored, a bushing supplied, and the gun re-rifled, which, in consequence of the necessity to dismount the gun and transport it to the factory, is an operation that not only involves much time, but great expense as well.

The object of my invention is therefore, to obviate this defect; and, to this end, the invention consists in the method of and means for applying a coating of metal under pressure to the eroded portions of the walls of the bore at or after each discharge of the gun, whereby a fresh metallic surface is presented thereby to the action of the gases and heat, all as will hereinafter more fully appear.

Referring to the accompanying drawing, which forms a part of this specification, Figure 1, is a side elevation, partly in axial section, of a portion of a gun, showing in side elevation a projectile constructed in accordance with my invention, and a cartridge arranged in the chamber in rear thereof; Fig. 2, a side elevation of a projectile constructed in accordance with my invention, with a portion at its butt broken away and shown in section, to more clearly illustrate the invention, and Fig. 3, an enlarged sectional fragment of the butt of a projectile, showing the arrangement of the abrasion band thereon.

In the several figures, like letters of ref-

erence are employed to designate corresponding parts.

A indicates the rear or breech portion of a cannon or other piece of heavy ordnance, which is or may be constructed of any ordinary or well known form. As shown in the drawing however, it follows the general line of construction of the ordinary modern breech-loading high power gun, and is provided with the usual rifled bore *a* and breech opening and closing mechanism (not shown), and also with a charge-receiving chamber *a*¹ at the rear end of the bore *a*, as is common with guns of this character as ordinarily employed. In being thus constructed, the gun, when in operation, receives within the chamber *a*¹ the required charge, comprising the projectile B and the bag of explosive C; and the discharge of the projectile therefrom is effected by burning the explosive within the bore *a* and chamber *a*¹, the result of which is to generate a sufficient volume of gas and set free the requisite amount of heat to violently expel the projectile from the bore of the gun and carry it forward in its trajectory to its place of destination. To accomplish this ejection and propulsion of the projectile at the excessively high speed and to the great distance desired, it is obvious that the pressure exerted by the consumption of the explosive within the bore of the gun is enormous and exceeds at times more than fifteen, if not twenty, tons to the square inch.

With guns of the present high power class and with the use of modern smokeless and other excessively strong acting explosives, the pressure exerted by its consumption is so extremely great, that in ejecting the projectile from the gun and carrying it forward in its flight, it acts upon the walls of the bore *a* with such a tremendous force that it erodes and eats them away to such an extent as to completely obliterate the lands *a*² between the grooves *a*³ of the rifling, and render the gun wholly useless after a certain number of shots have been fired, which, in practice, seldom or never exceed one hundred shots in all. I have discovered however that this erosion and eating away of the walls of the bore may be obviated in whole or in part, by applying to the surfaces of these walls, a metallic

coating under pressure at or before each discharge of the gun in which a projectile is, or is to be, employed. While the metals that may be adopted to this end are of various kinds, I have found that bronze, made up as an alloy from copper and tin is the most efficient for the purpose, since when forced against steel surfaces under great pressure, it adheres thereto so firmly and tenaciously as to almost amount to an actual weld, and when applied to the walls of the bore of a gun it thereby presents a fresh metallic surface for the action of the gases and heat generated and set free by the burning of the explosive. For applying this metallic coating to the interior of the walls of the bore of the gun, various means may be employed. I prefer however to adopt for the purpose the projectiles themselves. To this end, I make use of the ordinary projectile, which, constructed either in the form of a solid shot or otherwise, is provided with the usual conical body b and groove-engaging band b^1 , and supports the bronze coating material, which is preferably made in the form of a ring b^2 , and is disposed in a suitable groove b^3 formed circumferentially around the conical body b , in rear of the groove engaging band b^1 , as shown. This ring b^2 , which, for convenience of description I shall hereinafter designate an abrasion ring, is preferably though not necessarily made of the same diameter as the groove-engaging band b^1 whereby to engage with the lands a^2 , and, at the same time be pressed against the bottom of the grooves a^3 in moving along the bore a , as the projectile is ejected from the gun. In being thus engaged with the lands a^2 and pressed outward against the bottom of the grooves a^3 , it is obvious that the abrasion ring a^2 , in being carried forward by the projectile over any roughened or eroded surface in the walls of the bore a , will be engaged thereby and the portions thereof thus engaged will be abraded away by such engagement, with the result that the portions of the material thus abraded and carried away will, in consequence of the pressure exerted between the ring and the walls of the bore, be forced into the depressions formed in the walls of the bore by such erosion and thereby adhere so firmly to the material of the gun as to form a practically fixed surface of this bronze material upon the interior of the bore over the roughened portion thereof, against which the gases and heat may act at the next discharge of the gun. In order therefore to provide for pressing this abrasion ring b^2 outward into contact with the walls of the bore a with the requisite degree of pressure, the groove b^3 in which the ring is located, instead of being made with vertical side walls, has its front walls b^4 inclined forward from its inner to its outer edge, whereby to act as an expand-

ing means for the ring as the ring is forced forward upon it by the pressure of the gases acting upon its rear edge when the consumption of the explosive takes place to effect the discharge of the projectile; while to afford a freer and more efficient action of the gases upon the ring to force it forward upon the inclined walls of the groove b^3 when the explosive is consumed, the rear walls b^5 of this groove are inclined rearwardly to a slight degree from their inner to their outer edges, with an annular rabbet b^6 formed around their outer edge, whereby to permit of the engagement of appropriate tongs or other retracting means with the projectile when the withdrawal of the latter from the gun is desired. With the rear walls b^5 of the groove b^3 thus backwardly inclined, the free action of the gases evolved by the consumption of the explosive against the rear edge of the abrasion ring b^2 throughout its entire extent is permitted; and, in order to allow of the forward movement of this ring upon the inclined walls b^4 of the groove b^3 , and with a view to preventing it from fixedly adhering to the body b of the projectile when acted upon by the gases and heat, the groove b^3 is made somewhat wider than the ring b^2 and a layer of lubricating material b^7 , such, for instance, as graphite or plumbago is interposed between the front edge of the ring and the forward inclined walls b^4 of the groove b^3 , as shown. With the abrasion ring b^2 thus supported and carried by the projectile, a metallic coating is applied to any eroded or otherwise roughened surface that may be present within the bore a and firmly adhered or secured thereto at each discharge of a projectile from the gun. In the construction of the abrasion ring b^2 , the material of which it is composed, while possessed of a less degree of hardness than the material of the gun itself, is preferably somewhat harder than the groove-engaging band b^1 , whereby to resist the scraping action of this groove-engaging band in passing over and in contact with the material of the abrasion ring previously applied as a coating to the eroded or other roughened surfaces of the bore a . With the abrading ring b^2 thus secured to and carried by the projectile B, the walls of the bore of the gun will be unaffected thereby when it is passed over them and the walls are free from erosion or other roughness. When however these walls are eroded or otherwise roughened, then in the abrading ring being carried forward over them by the projectile, the abrasion of this ring by the roughness of the walls will be effected, and the portion thereof thus abraded away will be deposited in the depressions formed by such roughness and firmly adhered or secured therein, with the result that the portions thus coated with

the abraded material will present a smooth surface to the action of the gases and the heat respectively generated and set free at the next discharge of the gun, and so on.

5 From the foregoing therefore it will be seen, that I not only protect the bore of a gun from erosion by the action of the gases and heat respectively generated and set free by the discharge of the gun, but also provide means by which that protection is effected.

Having thus described the invention, and specified certain of the ways in which it is or may be carried into effect, I claim and 15 desire to secure by Letters Patent of the United States—

1. A projectile for resurfacing the roughened and eroded surface portions of gun bores, comprising a body portion, and a ring 20 structure of bronze formed with a beveled front surface whereby pressure exerted on

the rear of said ring will expand the same radially for causing the abrasion thereof by said roughened and eroded surface portions.

2. A projectile for resurfacing the roughened and eroded surface portions of gun bores, comprising a body portion, and a resurfacing projectile encircling member formed of bronze abraded by said roughened and eroded surface portions as the projectile is forced through the gun bore, the abraded portions of said encircling member being applied to the gun bore under pressure substantially at the time it is abraded.

In testimony whereof, I have hereunto set my hand in the presence of two witnesses this 19th day of April, 1910.

FREDERICK N. DU BOIS.
